UNITED STATES PATENT OFFICE

FRANK CARSON, OF DETROIT, MICHIGAN

DESIGN FOR A REFRIGERATOR BUFFET

Application filed April 7, 1933. Serial No. 47,720. Term of patent 14 years.

To all whom it may concern:

Be it known that I, FRANK CARSON, a citizen of the United States, residing at Detroit, county of Wayne, State of Michigan, have invented a new, original, and ornamental Design for a Refrigerator Buffet, of which the following is a specification, reference being had to the accompanying drawing forming part thereof.

The figure of the drawing is a perspective view of the refrigerator buffet, showing my new design.

The rear side of the structure shown in the drawing is similar to the front side which is illustrated except that the door shown in dotted outline on the front side does not appear on the rear side, and the end not shown in the drawing is a plane elevation similar to the exposed upper portion of the end shown.

I claim:

The ornamental design for a refrigerator buffet, as shown and described.

FRANK CARSON.
